UNITED STATES PATENT OFFICE.

ERNEST HAAS, OF MANCHESTER, ENGLAND.

STAMP-AFFIXING APPARATUS.

1,098,254.

Specification of Letters Patent. Patented May 26, 1914.

Application filed August 5, 1911. Serial No. 642,480.

To all whom it may concern:

Be it known that I, ERNEST HAAS, citizen of Switzerland, residing at Manchester, in the county of Lancaster, Kingdom of Great Britain, have invented certain new and useful Improvements in Stamp-Affixing Apparatus; and I do hereby declare the following to be a full, clear, and exact description of the invention, such as will enable others skilled in the art to which it appertains to make and use the same.

My invention relates to improvements upon an invention for which Letters Patent No. 956,526 have been granted to me for 15 "improvements in apparatus for affixing postage stamps, labels or the like and for selling postage stamps".

My present invention has for its object to improve the stamp feeding, stamp damping 20 and the envelop or the like delivery device described in the said specification whereby the apparatus is greatly simplified, the stamp feed rendered more accurate, accessible and observable and the stamps are 25 damped after they have been fed, the envelop or the like brought into its proper position below the plunger and the envelop or the like with stamp affixed delivered into a receptacle which may be collapsible. I attain these objects by the mechanism illustrated in the accompanying two sheets of 30 drawings in which—

Figures 1 and 4 are side views, the latter partly in section Fig. 1 showing the operative parts of the apparatus in their normal position, and Fig. 4 when the plunger has been depressed. Fig. 1^x is a detached front view. Fig. 2 is a plan of Fig. 1, the envelop or the like receptacle being in the former 40 shown collapsed and in the latter extended. Fig. 3 is a cross section of Fig. 4. Fig. 3^x is a sectional detailed view taken on the same plane as Fig. 3. Figs. 5 and 6 are respectively a side view and a sectional plan, and 45 Figs. 7 and 8 are back views, the latter partly in section, on an enlarged scale of the head of the apparatus constructed in accordance with my invention.

Similar letters refer to similar parts 50 throughout the several views.

a is the machine body, *b* the stamp ribbon, *c* the stamp ribbon spool, *d* the stamp ribbon feed table, *e* the stamp ribbon feed slide, *f* the feed foot, *g* the stamp severing 55 knife, *h* the plunger, *i* the stamp damping medium, *k* the water reservoir, *l* the envelop

or the like delivery roller, *m* the envelop or the like receptacle.

In carrying out my invention and referring to Figs. 1, 2, 3 and 4, I arrange the 60 stamp feed slide *f* at the side instead of in the middle above the stamp ribbon feed table *d* and feed foot with path approximately in the same horizontal plane as that of the said feed slide whereby the latter is brought in 65 full view of the operator and rendered more positive and reliable in action. The slide *e* is mounted in a bed formed in or on the body *a* of the machine and is under the influence of a spring *n* adapted to bring it 70 back to its normal position to abut against the machine body *a*. This slide has an arm reaching over the feed table *d* and having a boss *o* central with the feed table *d* in which is mounted a rod *p* carrying at its lower end 75 the feed foot *f*. To reduce the friction in raising and lowering the said feed foot and at the same time secure a rigid fit when lowering, this rod has a conical part *q* fitting into a correspondingly shaped hole in the 80 boss *o* and is placed under the influence of a spring *r* which tends to press the feed foot *f* upon the stamp ribbon *b*. The upper end of this rod has secured thereto a knob *s* with a cam face *t* adapted to work against a similar 85 face *u* on a cap *v* on the top of the boss *o*, see Figs. 1 and 3, whereby the feed foot *f* can be readily raised and lowered by hand to facilitate the insertion and adjustment of 90 the stamp ribbon *b*.

The front part of the machine body *a* is cranked sidewise and has an upwardly extending arm *w* in which is mounted the plunger *h*. The arm *w* has secured in front a cap *x* leaving a slot *y* at the side of the 95 plunger. Through this slot a stud *z* projects from the plunger to which is pivoted a rod 2 having at its free end an adjustable abutment 3. This abutment has a shank 4 adapted to slide in a block 5 pivoted to an arm 6 100 secured to a shaft 7 mounted in bearings on the feed slide *e*. The shaft 7 has also secured to it an arm 8 adapted to bear against a stud 9 secured to the rod *p* of the feed foot *f* and passing through a slot in the boss *o*. 105 Each time the plunger *h* is depressed the abutment on the rod 2 connecting the plunger with the feed slide *e* contacts with the block 5 which causes the arm 6 which carries the block 5 to turn the shaft 7 to which it is secured and by means of the arm 8 110 raise the feed foot *f*.

On the outside of the machine body *a*, I mount a shaft 10 carrying a finger 11 adapted to arrest the feed slide *e* during its inward movement and thereby cause the 5 abutment 3 to leave the block 5 and release and allow the feed foot *f* to instantly drop upon the stamp ribbon *b*. The shaft 10 has also secured thereto an arm 11* which is actuated by the plate *h'* of the plunger *h*. 10 when rising, the plate *h'* contacting with the arm 11* at the end of each upward movement of the plunger which causes the shaft 10 to turn and the finger 11 secured thereto to release the feed slide *e* and thus 15 the feed foot *f* to feed the stamp ribbon *b*.

In order to vary the amount of feed of the stamp ribbon *b*, the shaft 10 has a screw threaded end carrying two nuts *a'* by means of which the longitudinal position 20 of the shaft 10 and hence the finger 11 thereon is rendered variable in relation to the feed slide *e*, while the spring around the shaft 10 insures the finger 11 being brought into the path of the slide *e* when 25 required, one end of the said spring being secured and the other pressing upon the said finger in a rotary sense. The feed table *d* is fulcrumed to a stud 12 projecting from the machine body *a* and thus is readily removed when required. 30 The top of the feed table *d* has a groove 13 in width corresponding with the stamp ribbon *b* and containing a plate 14 removably secured and adapted to rest upon the 35 stamp ribbon to keep it flat and extending through a groove 15 in the underside of the feed foot *f* to the front of the feed table *d*. The stamp ribbon *b* passes underneath the plate 14 and can be adjusted by a roller 16 mounted on the feed table *d* at the back of 40 the plate 14. To the rear of the arm 10 of the machine body is fulcrumed an angular lever 17 adapted to be actuated by the feed foot *f* (or slide) on the outward movement 45 thereof to press the front end of the plate 14 upon and thereby hold the stamp ribbon in position upon the table *d* while severing a stamp.

In order to facilitate the use of stamp 50 ribbons of different values on spools *c* I mount the same in such a manner on a stud 18 carried by a bracket 19 at the rear of the feed table *d*, that the spools can be brought in and out of use as may be desired, see Fig. 2.

Referring to Figs. 5, 6, 7 and 8, in order 55 to permit of damping the stamp to be affixed after it has been severed from the ribbon by the knife *g*, I fulcrum a damping device to the arms or studs 20 of the rollers 21 supporting the stamp while being severed, which rollers in this case are grooved. The said damping device consists of a plate 22 fulcrumed to the roller studs 20 60 and extending underneath the rollers 21.

The inner side of each of the plates 22 has a number of tubes 23 projecting upward between and at each side of the grooves 24 in the rollers 21. The upper ends of the tubes 23 are each furnished with a flexible 70 nipple 25 projecting slightly from the periphery of the rollers 21 capable of yielding and containing a damping medium *i*, say fibrous threads passing from the tubes 23 to the water receptacle *k* and incased in a 75 flexible tube 26. The water receptacle *k* is pivoted underneath the feed table *d* to the base of the apparatus so as to be capable of being turned from underneath the feed table *d* to facilitate filling with water. 80 To each of the plates 22 is secured a cover 27 extending at each side and between the roller grooves 24 to near the nipples 25, which covers prevent the stamp from dipping between and at the side of the grooves 85 24. Normally the free ends of the nipples 25 are below the top level of the rollers 21, see Fig. 7, and when required to damp the stamp are raised, say by a projection 28 on the plunger *h* coming into contact with an 90 abutment 29 on and turning the plate 22 thereby bringing the free ends of the nipples 25 into contact with the gummed side of the stamp supported on the rollers 21 in which position they remain locked during 95 the descent and opening of the legs 30 carrying the rollers 21 and the damping of the stamp by the nipples 25 by pins 31 on the plates 22 engaging in spring catches 32, see Fig. 8. After the stamp has been 100 damped, the further downward movement of the plunger *h* causes the plates 22 carrying the nipples 25 to be turned back into their normal position, say by the plunger *h* contacting with a projection 33 on each of the plates 22, see dotted lines Fig. 8. The legs 30 are opened by their free ends contacting with cam faces 34 formed on the *T* piece 35 secured to the machine arm or cap *x*. The delivery roller *l* I mount in 110 the machine base parallel with the front of the machine, Figs. 1, 2 and 4, and in connection therewith I employ a receptacle *m* which may be carried by a frame 36 slideable in or on the machine base for the purpose 115 of collapsing the receptacle *m* when the machine is not in use, see Fig. 2. The delivery roller *l* is rotated by means of a pinion 37 on the roller and a rack 38 in gear therewith actuated from the stamp 120 feed or plunger *h* by an arm *b'* secured to the feed slide *e* engaging in a recess at the inner end of the rack 38 in such a manner that on the down stroke of the plunger, the roller *l* turns inward and on the upstroke outward. I also employ a guide 39 on the base 125 of the machine against which the envelop or the like is moved by the delivery roller *l*, Figs. 1 and 2 when placing it on the machine base which insures the stamps being 130

affixed always in the same position in respect of the top edge of the envelop or the like.

I claim:

1. In an apparatus for affixing postage stamps and the like, a stamp affixing plunger, a stamp ribbon feed table, a stamp ribbon feed slide at the side of the said table, a stamp ribbon feed foot carried by the said slide and located over the said table and means for actuating the said slide from the said plunger, the path of the said slide being approximately in the same horizontal plane as that of the said feed foot and the path of the said feed foot in a vertical plane with the said plunger, substantially as and for the purpose set forth. 70
2. In an apparatus for affixing postage stamps and the like, a stamp affixing plunger, a stamp ribbon feed table, a stamp ribbon feed slide at the side of the said table, and a stamp ribbon feed foot carried by the said slide and located over the said table, the said slide having a conical socket and the said feed foot a coned rod fitting the said socket, substantially as and for the purpose specified. 75
3. In an apparatus for affixing postage stamps and the like, a stamp affixing plunger, a stamp ribbon feed table, a stamp ribbon feed slide at the side of the said table, a stamp ribbon feed foot carried by the said slide and located over the said table, the said slide having a conical socket and the said feed foot a coned rod fitting the said socket, a knob at the end of the said rod and cam faces on the said knob and the said socket in operative connection with each other, substantially as and for the purpose specified. 80
4. In an apparatus for affixing postage stamps, and the like, a stamp affixing plunger, a stamp ribbon feed table, a stamp ribbon feed slide at the side of the said table, and a stamp ribbon feed foot carried by the said slide and located over the said table, a plate secured to the said feed table extending through a groove in the said foot and adapted to continuously rest upon the stamp ribbon on the said table, substantially as and for the purpose set forth. 85
5. In an apparatus for affixing postage stamps and the like, a stamp affixing plunger, a stamp ribbon feed table, a stamp ribbon feed slide at the side of the said table, and a stamp ribbon feed foot carried by the said slide and located over the said table, a lever pivoted to the frame of the apparatus operated by the said feed foot and adapted to hold the stamp ribbon longitudinally in position upon the feed table while severing a stamp, substantially as and for the purpose set forth. 90
6. In an apparatus for affixing postage stamps and the like, a stamp affixing plunger, a stamp ribbon feed table, a stamp ribbon feed slide at the side of the said table, and a stamp ribbon feed foot carried by the said slide and located over the said table, a cross shaft mounted on the said foot slide 95
- an arm secured upon the end of the said shaft adjacent to the said feed foot adapted to raise the latter, an arm secured to the other end of the said shaft, a block pivoted thereto and a rod pivoted to the said plunger and adapted to slide in the said block and the said rod having an abutment to contact with the said block when the said feed slide moves outward, substantially as and for the purpose set forth. 100
7. In an apparatus for affixing postage stamps and the like, a stamp affixing plunger, a stamp ribbon feed table, a stamp ribbon feed slide at the side of the said table, and a stamp ribbon feed foot carried by the said slide and located over the said table, a side shaft mounted on the frame of the apparatus, an arm and a finger secured thereto the former being under the control of the said plunger and the latter adapted 105
- to arrest the said feed slide on its inward movement to allow the feed foot to drop, substantially as and for the purpose specified. 110
8. In an apparatus for affixing postage stamps and the like, a stamp affixing plunger, a stamp ribbon feed table, a stamp ribbon feed slide and foot, two vertically movable stamp supporting arms having each at the lower end a stud, a roller and a damping 115
- medium on each of the said studs located below the periphery of the said rollers while the stamp rests upon them and means for turning the said damping medium against the stamp when the said arms move outward to damp the stamp from the middle to each side thereof and means for bringing the said damping medium into their normal position again, substantially as and for the purpose specified. 120
9. In an apparatus for affixing postage stamps and the like, a stamp affixing plunger, a stamp ribbon feed table, a stamp ribbon feed slide and foot, two vertically movable stamp supporting arms having each at the lower end a stud, a roller and a damping 125
- medium on each of the said studs located below the periphery of the said rollers while the stamp rests upon them and means for turning the said damping medium against the stamp when the said arms move outward to damp the stamp from the middle to each side thereof, means for bringing the said damping medium into their normal position again, and means for locking the same in their operative and inoperative position, substantially as and for the purpose set forth. 130

bon feed slide and foot, two vertically movable stamp supporting arms having each at their lower ends a stud, a roller and a damping medium on each of the said studs, comprising a plate pivoted thereto and carrying a series of tubes each containing a capillary damping medium and furnished with a flexible nipple, substantially as and for the purpose specified.

10 11. In an apparatus for affixing postage stamps and the like, a stamp affixing plunger, a stamp ribbon feed table, a stamp ribbon feed slide and foot, two vertically movable stamp supporting arms having each at their lower ends a stud, a roller and a damping medium on each of the said studs, and a water reservoir pivoted to the base of the apparatus supplying the said damping medium with water, substantially as and for the purpose specified.

15 12. In an apparatus for affixing postage stamps and the like, a stamp affixing plunger, a stamp ribbon feed table, a stamp rib-

bon feed slide and foot, a delivery roller mounted in the base of the apparatus, a pinion secured thereto and a rack in gear with the said pinion actuated by the said feed slide for imparting motion to the said roller, substantially as and for the purpose set forth.

20 13. In an apparatus for affixing postage stamps and the like, a stamp affixing plunger, a delivery roller mounted in the base of the apparatus and actuated from the said plunger, a frame slidably attached to the front of the base of the apparatus and a bag suspended from and capable of being extended or collapsed by the said frame, substantially as and for the purpose set forth.

25 In testimony whereof I have affixed my signature in presence of two witnesses.

ERNEST HAAS.
